(57) **CLAIM**

The ornamental design for a fastening device for rack-mount as shown and described.

DESCRIPTION

FIG. 1 is a front perspective view of a fastening device for rack-mount according to the present invention.

FIG. 2 is a left-side view of the fastening device for rack-mount according to the present invention. The right-side view is the same.

FIG. 3 is a bottom view of the fastening device for rack-mount according to the present invention; and,

FIG. 4 is a back perspective view of the fastening device for rack-mount according to the present invention.

The broken lines and areas within depict portions of the fastening device for rack mount that form no part of the claimed design.
